UNITED STATES PATENT OFFICE.

EDWARD W. THOMAS, OF STOCKTON, CALIFORNIA.

OIL-BURNER.

No. 918,711.

Specification of Letters Patent. Patented April 20, 1909.

Application filed February 28, 1908. Serial No. 418,187.

To all whom it may concern:

Be it known that I, EDWARD W. THOMAS, a citizen of the United States, residing at Stockton, in the county of San Joaquin and 5 State of California, have invented certain new and useful Improvements in Oil-Burners; and I do declare the following to be a full, clear, and exact description of the same, such as will enable others skilled in the art 10 to which it appertains to make and use the same, reference being had to the accompanying drawings, and to the characters of reference marked thereon, which form a part of this application.

15 This invention relates to improvements in oil burners and particularly to that class used in connection with stationary or locomotive fire boxes of all kinds, the object of the invention being to produce a burner 20 having a fan shaped discharge or burning nozzle, whereby the heat will be evenly and effectively distributed throughout the fire box without the annoyance of expansion and contraction consequent upon uneven distribution, so often now encountered, thus 25 doing away with the necessity of brick arches as now used; also to produce a burner which will economize fuel and prevent the accumulation of carbon or other deleterious 30 matter in the ash pan; also to provide a simple and inexpensive burner for the purpose. These objects I accomplish by means of a main casing having oil and steam inlets and provided with a substantially fan 35 shaped outlet for each, there being a fan shaped burner plate or lip onto which the oil flows, the steam sweeping or discharging directly across the surface of said plate, thus thoroughly atomizing and mixing with the 40 oil, as is necessary to produce perfect combustion; also by such other and further construction as will appear by a perusal of the following specification and claims.

In the drawings similar characters of reference indicate corresponding parts in the several views.

Figure 1 is a perspective view of the complete burner. Fig. 2 is a longitudinal section of the same. Fig. 3 is a perspective 50 view of the burner lip or plate showing an adjustable gasket or guide plate thereon. Fig. 4 is a view similar to Fig. 3 showing fixed raised gasket or guide plates on the same. Fig. 5 is a top plan view of the adjustable guide plates.

Referring now more particularly to the

characters of reference on the drawings 1 designates the main casing of the device provided with an oil inlet 2 and a steam inlet 3, the inlet 2 reducing to an oblong passage 60 way 4 flaring into a substantially fan shaped discharge nozzle 5. Similarly the inlet 3 reduces to an oblong passage way 6, over the mouth of which is suitably secured a vertical plate 7 provided with an outwardly extending flat fan shaped burner plate or lip 8, the same being spaced but a minute distance from the roof of the passage 6 and held in such spaced position by means of fixed or adjustable guide plates or gaskets 65 9, the said member 8 being beveled downward at its inner end as at 10 to permit the steam to readily pass into the space between said plate and the roof of said passage 6 as shown. The gaskets 9 are constructed to 70 conform to the fan shape of the lip 8 and the outer edges of the members 5 and 8 are provided with a curve to carry out the scheme of the fan shape of those members and thus aid in the operation thereof. The casing is 75 formed with projecting lugs 11 forming side walls or guides at each end of the plate 8, the members 9 fitting snugly against lugs 11, since the bottoms of said lugs are formed flush with the roof of the passage 6. 80

85 12 is a centrally orificed lug on the rear of the casing 1 for the purpose of securing the burner to the rear plate of the mud ring of the fire box.

In practice the oil is fed into the inlet 2 90 and flows through the passage way 4 out the discharge nozzle 5 onto the plate or lip 8. The steam passes into the inlet 3 and passes through the passage way 6 and by reason of the reduced space between the 95 plate 8 and the roof of the passage 6 it escapes with great force through the space 10 over the plate or lip 8 and thus picks up the oil flowing onto said plate and thoroughly atomizes and gasifies the same 100 as is required, the flame spreading evenly throughout the fire box in a substantial fan shape by reason of the construction described. This fan shaped effect is of great importance, since it throws the flame equally 105 to all parts of the fire box, thus overcoming the difficulties set forth in the statement of the objects of this invention.

The members 9 form guides for the sweep of the steam and oil and may be either fixed 110 as shown in Fig. 4, or adjustable as shown in Fig. 3 for the purpose of changing the

size of the flame, and if made adjustable they are formed with elongated slots 9^a fitting over suitable bolts or pins for the purpose.

5 The members 11 prevent the oil from overflowing on the side edges of the lip or plate 8 and also aid in directing the sweep of the flame.

From the foregoing description it will be 10 readily seen that I have produced a burner which substantially fulfills all the objects of the invention as set forth herein.

While this specification sets forth in detail the present and preferred construction 15 of my invention, still in practice such deviations from such detail may be resorted to as do not form a departure from the spirit of the invention.

Having thus described my invention what 20 I claim as new and useful and desire to secure by Letters Patent is:—

1. An oil burner comprising a body portion having an oil and a steam conduit, such

oil conduit projecting a greater distance forward than said steam conduit, projecting 25 side lugs on either side of said oil conduit, a plate disposed over the mouth of said steam passage, a horizontal projecting lip projecting forward from said plate and clear of said body and spaced a slight distance from the roof of said steam conduit, and gaskets disposed between said lip and said side lugs.

2. An oil burner comprising a body portion having oil and steam conduits, a lip 35 projecting forward from said steam conduit, gaskets disposed between said lip and the roof of said steam conduit, said gaskets being adjustable longitudinally with respect to said lip, as set forth.

In testimony whereof I affix my signature in presence of two witnesses.

EDWARD W. THOMAS.
